Inventor

Henry Higgin,
By Attorney,
Christison & Richards.

UNITED STATES PATENT OFFICE.

HENRY HIGGIN, OF NEWPORT, KENTUCKY, ASSIGNOR TO THE HIGGIN MANUFACTURING COMPANY.

CURTAIN-KNOB.

SPECIFICATION forming part of Letters Patent No. 715,380, dated December 9, 1902.

Application filed October 6, 1900. Serial No. 32,315. (No model.)

To all whom it may concern:

Be it known that I, HENRY HIGGIN, a citizen of the United States, residing at Newport, in the county of Campbell and State of Kentucky, have invented certain new and useful Improvements in Curtain-Knobs, of which the following is a specification.

The object of my invention is to provide a curtain-knob for carriages which is light and durable and which may be manufactured by machinery, thus greatly reducing the cost.

My invention consists of the parts, combinations, and arrangements of parts and the method of producing them, hereinafter described and claimed.

In the drawings, Figure 1 is a side view of a knob embodying my invention in position; Fig. 2, a section of Fig. 1; Fig. 3, the blank from which the knob is formed; Figs. 4, 5, 20 6, and 7, sections of the knob in the successive steps of manufacture.

In constructing the knob a circular blank A, Fig. 3, is stamped into cup shape, as indicated in Figs. 4 and 5, then the open end 25 compressed to form a narrow neck, as indi-

cated in Figs. 6 and 7, and the hole a punched or drilled in the bottom to permit the passage of fastening means. In securing the knob in position a rivet B, with a head b large enough to serve as the head of the knob, is used. The 30 walls a' of shell A are slightly curved inward, so that the tension of fastening tends to spread the shell at its base, which tendency is resisted by the annular flange a^2 , thus forming a very strong combination adapted to permit the rivet B to be secured very tightly without buckling the shell.

I claim as my invention—

A curtain-knob consisting of a shell formed of a single piece of ductile metal, having a 40 narrow neck and a spreading base, provided with an annular flange adapted to resist the spreading tendency, secured in position by a fastener provided with a head large enough to serve as the head of the knob, substantially as and for the purpose set forth.

HENRY HIGGIN.
